(57) **CLAIM**

The ornamental design for a mobile medical imaging scanner, as shown and described.

DESCRIPTION

FIG. 1 is a perspective view of a mobile medical imaging scanner having a design thereon in accordance with an embodiment of the present invention.

FIG. 2 is a side elevational view of the mobile medical imaging scanner of FIG. 1.

FIG. 3 is a rear elevational view of the mobile medical imaging scanner of FIG. 1.

FIG. 4 is a front elevational view of the mobile medical imaging scanner of FIG. 1; and,

FIG. 5 is a top plan view of the mobile medical imaging scanner of FIG. 1.

The broken lines in the drawing views are included for the purpose of illustrating portions of the mobile medical imaging scanner that form no part of the claimed design.

1 Claim, 5 Drawing Sheets

FIG. 2

FIG. 3

FIG. 4

FIG. 5
